UNITED STATES PATENT OFFICE.

HENRY E. MOLIARD, OF HICKSVILLE, NEW YORK.

FILING ELEMENT.

Application filed May 17, 1927. Serial No. 191,966.

This invention relates to filing elements for indexes and filing systems where the elements such as cards, leaves, or sheets are to be disposed in overlapping groups in a loose leaf binder having a plurality of impaling means such as rings, posts, pins or bars so that a portion of each element of each group is visible for indexing purposes. In such a series of elements the removal or insertion of a single element of a group necessarily involves the temporary displacement of the entire group and if the elements of a group are not held together during removal and replacement they become disarranged and must be replaced one by one thus involving considerable waste of time. Furthermore with the present type of elements an especial arrangement of the impaling means is necessary in order to adapt the elements for use whereas with my invention the elements can be employed with binders in which the spacing of the impaling elements varies and in which fewer impaling elements are employed than usual. The object of this invention is to interlock the elements whereby (1) they can be removed and replaced in groups without becoming disarranged, (2) they can be adjusted to vary the amount of visible matter on each element and (3), they can be adjusted to vary the space between their binder perforations to align them with respect to the impaling elements. The invention comprises providing each element such as a card, leaf or sheet with at least one binder perforation and with means for interlocking with adjacent elements to form a series which can be manipulated as a unit to avoid disarrangement during removal and replacement of the series with respect to the engaging means. The interlocking means are such as to permit the elements to be adjusted with respect to each other so that the amount of visible matter on each card can be varied and to permit the series of elements to be so adjusted that at least two of the binder perforations of the series can be spaced to engage with the impaling means such as binder rings so that the series of cards can be used in binders having two or more rings and can be therein handled as a unit. The

interlocking means of one form is also such as to permit of the adjustment of the elements with respect to each other even while they are interlocked. 55

The invention more specifically comprises providing each element with at least one binder perforation and with a tongue to engage in a slit in another element to interlock the elements. By varying the amount to which the tongues project into the slits the series can be arranged so that if the binder only has two rings, two perforations in the series will connect with these rings and permit the series to be handled as a unit. 60 65

The invention is illustrated in the drawings, of which,

Fig. 1 is an elevation of a sheet element of one form of my invention.

Fig. 2 is another form thereof.

Fig. 3 is an elevation with portions broken away showing a series of elements of the form shown in Fig. 1 disposed in a loose leaf binder.

Fig. 4 is a partial view showing a series of 75 interlocked elements of the form shown in Fig. 2.

Fig. 5 is a vertical section taken through the tongues of Fig. 3.

In the form of invention shown in Fig. 1, the element is a card 10 having a plurality of binder perforations 11 along one edge. A tongue 12 is cut from the material of the card extending parallel to the line of perforations and including some of them to interlock with another element. A slit 13 is spaced from the inner end of the tongue and is adapted to receive a similar tongue on another element. 80 85

In Fig. 2 a card 14 is shown with a plurality of binder perforations 15 along one edge and a tongue 16 is disposed in one corner at an angle and adjacent the edge along which the perforations 15 are disposed. Spaced along the same edge with tongue 16 are one or more slits, such as 17, adapted to receive 90 95 similar tongues on other elements.

In Fig. 3 is shown a loose leaf binder 18 having binder rings 19, engaging a series of cards 20 to 25, inclusive, which are of the form illustrated in Fig. 1. The tongue of one card is adapted to be received in the slit of the adjacent card to interlock them and the 100

length of the tongue permits the amount of overlap to be varied while permitting the binder holes to be placed in registration with the rings. This variation in the overlap in 5 this form of the invention can be effected even while the cards are interlocked. In this figure some of the cards are shown overlapped a different amount than others.

In Fig. 4, a series of cards 26 to 29, inclusive, and of the form shown in Fig. 2 are interlocked with different overlaps. It is clear 10 that the tongue 16 of one card can be inserted in any one of the slits 17 to interlock the elements and the amount of overlap will be determined by the slit thus employed.

While in most cases loose leaf binders have 20 more than two rings, in some instances six or seven rings, it is apparent that this invention permits a series of overlapping cards to be placed in a binder regardless of the number of rings. Each card in common practice is generally provided with at least two perforations and by adjusting the engagement of the tongue in the slits the space between the 25 perforations can be varied to align the perforations with the rings.

Therefore a series of elements such as cards, leaves or sheets can be interlocked and held 30 together in groups in a predetermined alignment such as with respect to a series of binder perforations and the amount of overlap can be varied even while the cards are interlocked to permit the visible portion of the cards to be changed. In handling cards thus connected 35 to remove them from or replace them in a binder, the cards do not become disarranged as this manipulation is made exceedingly simple. It is possible to change the length, dimensions and relative disposition of the 40 tongues and slits with respect to each other and the edges of the elements, and the character of the perforations may be different from that shown without departing from the spirit of the invention.

45 I claim:

1. A filing element having at least one binder perforation and means for interlocking it with a similar element to hold them together as a unit but adapted to permit their 50 adjustment whereby the space between the perforations can be varied to align them with respect to a plurality of impaling means on the binder.

2. A pair of filing elements each having at 55 least one binder perforation and means adjustably interlocking them to hold them together as a unit but adapted to permit the space between the perforations to be varied to align them with respect to a plurality of 60 impaling means on the binder.

3. A series of filing elements each having at 65 least one binder perforation and having means for adjustably interlocking the elements together in overlapped relation for insertion as a unit in a binder having a series

of evenly spaced impaling members, such means allowing the members to be so inserted with more than one degree of overlap.

4. A filing element having a binder perforation and a plurality of slits and a tongue 70 adapted to interlock with any one of the plurality of slits in a similar element to hold them together as a unit, thereby permitting the space between the perforations to be varied to align them with respect to a plurality 75 of impaling means on a binder.

5. A series of filing elements each having at least one binder perforation and a plurality of slits, and each having a tongue adapted to interlock with any one of the 80 plurality of slits in an adjacent element of the series to hold them together in overlapped relation and allow them to be adjusted for insertion as a unit in a binder having a series 85 of evenly spaced impaling elements with more than one degree of overlap.

6. A filing element having at least one binder perforation and a slit adjacent one edge, a tongue disposed adjacent said edge to interlock with the slit in an adjacent similar 90 element, the space between the tongue and the slit determining the amount of visible area of the elements but permitting the elements while held together as a unit to be adjusted to align the perforations with a 95 plurality of impaling means in a binder.

7. A filing element having at least one binder perforation and a slit adjacent one edge, a tongue adjacent said edge to interlock with the slit on an adjacent similar element, the space between the tongue and the slit determining the amount of visible area of each element but permitting the elements while held together as a unit to be adjusted to align the perforations with a plurality of 100 impaling means on a binder, the area of the tongue including at least one perforation.

8. A filing element having at least one binder perforation adjacent one edge and a plurality of spaced slits disposed within the 110 area of the element and disposed at an angle with respect to said edge, a tongue formed at one corner of the element at a similar angle to said edge and adapted to interlock with slits on an adjacent similar element, the space 115 between the tongue and the respective slits determining the amount of matter visible on the overlapping margin of any element and also permitting further incidental adjustment of the perforations with respect to the 120 impaling means on a binder.

9. A series of filing elements each having at least one binder perforation and having means for adjustably interlocking the elements together in overlapped relation for insertion as a unit in a binder having a series 125 of impaling members, such means allowing the members to be so inserted with more than one degree of overlap.

10. A series of filing elements each having 130

at least one binder perforation and a plurality of slits, and each having a tongue adapted to interlock with any one of the plurality of slits in an adjacent element of the series to hold them together in overlapped relation and allow them to be adjusted for insertion as a unit in a binder having a series of im-

paling elements with more than one degree of overlap.

Signed at New York city in the county of 10 New York and State of New York this 16th day of May A. D. 1927.

HENRY E. MOLIARD.
